UNITED STATES PATENT OFFICE

MORTIMER W. FISH, OF DAYTON, OHIO, ASSIGNOR TO DELCO-LIGHT COMPANY, OF DAYTON, OHIO, A CORPORATION OF DELAWARE

ELECTRICAL APPARATUS

Application filed September 26, 1923. Serial No. 664,834.

This invention relates to electric motors, and particularly to motors of the induction type wherein the motor is started from rest through the agency of armature circuits including brushes and a commutator, but after a certain speed has been attained the commutator is short circuited and the motor operates as an induction motor.

The objects of the present invention include provision of speed responsive means for short circuiting the commutator and for permitting the brushes to travel with the commutator in order to eliminate needless noise and brush wear.

Other and further objects and advantages of the present invention will be apparent from the following description, reference being had to the accompanying drawings, wherein a preferred form of embodiment of the present invention is clearly shown.

In the drawings:

Fig. 1 is an end view of an electric motor provided with the present invention, the end cover plate being removed.

Fig. 2 is a fragmentary sectional view taken substantially on the line 2—2 of Fig. 1, showing certain parts in normal position.

Fig. 3 is a fragmentary sectional view showing the parts in Fig. 2 in positions corresponding to a certain speed of operation of the motor.

The motor includes a field which in the drawings is represented by field frame 20 within which rotates an armature provided with a commutator 21. Commutator 21 includes a plurality of bars 22 clamped in position by means of clamping ring 23 and screws 24 upon a sleeve 25. The sleeve 25 is held in position upon the armature shaft 26 by means of a washer 27, a hub 28 and a nut 29 threaded on the end 30 of shaft 26.

A plurality of brushes 31 bear against the commutator 21, each brush is attached by a screw 32 to a brush arm 33 pivotally mounted on a stop 34 attached to a plate

35. Plate 35 is provided with a central aperture for receiving the hub 28. Plate 35 may rotate with the armature or may be held in a stationary position. The means for maintaining plate 35 stationary comprises a stationary disk 36 attached to the shell 20 in any convenient manner and provided with lugs 37 located diametrically opposite and each is provided with an inwardly projecting portion 38 adapted to be received by either of the two diametrically opposite notches 39 provided in the brush arm plate 35. The brushes 31 are held in yielding engagement with the commutator 21 by means of springs 40 connecting adjacent brush arms 33 as shown in Fig. 1.

The speed responsive means of the motor armature for short circuiting the commutator bars 22 and for releasing the brushes from the device which normally maintains the brushes stationary so that the brushes may turn with the commutator after a certain armature speed has been reached, comprises a plurality of weight elements 41 pivoted at 42 upon the hub 28 and provided with rollers 43 which bear against a disk 44. From disk 44 pressure may be transmitted to the left as shown in Fig. 3 to disk 45, brush arm plate 35, disk 46, disk 47, contact 48 and spring 49 which bears against the washer 27.

The operation of this invention is as follows:

Normally, or when the armature is at rest, the speed responsive elements 41 are in position as shown in Fig. 2. The spring 49 maintains the parts 48, 47, 46, 35, 45 and 44 in the position shown in Fig. 2 pressed as far as possible toward the rollers 43 and the weights 41. The inward position of weights 41 is limited by stops 41^a which bear against the hub 28. The brushes 31 are connected together electrically as well as mechanically as shown so that the motor initially operates as a repulsion motor. After

a certain armature speed has been attained, the weight elements 41 will move into the position shown in Fig. 3, thereby causing the contact member 48 to engage the bars 22 of the commutator 21, and causing the brush arm plate 35 to be released from engagement by the lugs 37. Therefore, the commutator bars 22 will be short circuited and the brushes will be permitted to turn with the commutator. Since the brushes may turn with the commutator during the normal operation of the motor instead of remaining stationary, noise and brush wear have been eliminated.

15 The construction and arrangement of the mechanism is such that ready access may be had thereto without disassembling the motor. Since the brush retaining disc 36 is carried directly by the field frame and the 20 short circuiting device is located at the same end of the motor and adjacent the end of the commutator, it is necessary only to remove an end cover 50 in order to have access to the mechanism. The removal of the cover 25 does not in any manner affect the operation of the motor. In this manner the attendant can view the performance of the mechanism.

While the form of embodiment of the present invention as herein disclosed, constitutes a preferred form, it is to be understood that other forms might be adopted, all coming within the scope of the claims which follow.

What is claimed is as follows:

35 1. An electric motor, comprising in combination, a rotating commutator, brushes engaging said commutator, a contact adapted to engage said commutator for short circuiting the bars thereof, centrifugally operated 40 weights adjacent the end of the commutator, a brush supporting member disposed between said contact and weights, said member being adapted to be moved longitudinally by the weights to move said contact into engagement with the commutator, and means 45 for preventing the rotation of said member, said means being rendered inoperative after a predetermined longitudinal movement of said brush supporting member, whereby the 50 brushes rotate with the commutator.

2. An electric motor, comprising in combination, a rotating commutator, brushes engaging said commutator, a contact adapted to engage said commutator for short circuiting the bars thereof, centrifugally operated 55 weights adjacent the end of the commutator, a brush supporting member disposed between said contact and weights, said member being adapted to be moved longitudinally by the weights to move said contact into engagement with the commutator, and means 60 for preventing the rotation of said member, said means being rendered inoperative after a predetermined longitudinal movement of 65 said brush supporting member, whereby the

brushes rotate with the commutator, and a longitudinally disposed spring disposed between the weights and the commutator and adapted to force said contact out of engagement with the commutator and return said brush supporting member to its non-rotating position when the speed of the motor decreases to a predetermined amount.

In testimony whereof I hereto affix my signature.

MORTIMER W. FISH.
